CLAIM

The ornamental design for a fire extinguisher case, as shown and described.

DESCRIPTION

FIG. 1 is a perspective view of a fire extinguisher case in a closed position.

FIG. 2 is a front view of the fire extinguisher case of FIG. 1.

FIG. 3 is a top view of the fire extinguisher case of FIG. 1. FIG. 4 is a first side view of the fire extinguisher case of FIG. 1.

FIG. 5 is a back view of the fire extinguisher case of FIG. 1.

FIG. 6 is a bottom view of the fire extinguisher case of FIG. 1; and,

FIG. 7 is a second side view of the fire extinguisher case of FIG. 1.

The broken lines illustrates portions of the fire extinguisher case and form no part of the claimed design.
